ATTORNEYS.

UNITED STATES PATENT OFFICE.

ALEXANDER BOYNTON, OF SAN ANTONIO, TEXAS.

CROWN BLOCK.

Original application filed April 27, 1925, Serial No. 26,251. Divided and this application filed April 28, 1926. Serial No. 105,296.

This invention relates to an improvement in crown blocks, designed for use with gin poles and especially adapted to facilitate stringing up for the purpose of pulling rods and otherwise caring for wells, particularly oil wells. The cost of derricks ranges so high that most operators in small producing fields use derricks for drilling only. When the well has been drilled a gin pole is set up over the well for the purpose of operating the same.

The present application is a division of my co-pending application filed April 27, 1925, Serial Number 26,251.

The object of the invention is to provide a novel form of crown block for use with a gin pole, the crown block being of simple and durable construction, reliable and effective in operation and easy and comparatively inexpensive to manufacture. The crown block is so constructed and organized as to be properly and firmly supported on the gin pole while providing the desired mounting for the blocks or pulleys without interfering with the guy lines and while providing a maximum amount of clearance between the pulleys and the well whereby to facilitate the removal and handling of long sections of tubing.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in side elevation showing a crown block embodying the present invention, the upper ends of the gin pole being illustrated in dotted lines.

Figure 2 is a view in rear elevation of the crown block shown in Figure 1,

Figure 3 is a plan view of the crown block, and

Figure 4 is a sectional view on the line 4-4 of Figure 1.

Referring to the drawings, the numeral 1 designates generally a gin pole. At the upper end of the gin pole a crown block, designated generally at 10, is provided. The crown block 10 includes a main supporting plate 11 designed to rest on the top of the gin pole and having integral depending flanges 12 engageable with the front and

back faces of the upper end of the gin pole to prevent backward or forward movement of the crown block. Centrally of the plate 11 an internal web 13 is formed and extends vertically downwardly from the plate. The web 13 fits in between the standards 2 of the gin pole when a pair of standards are employed. If a gin pole having a single mast or standard is used, the mast or standard has a centrally disposed vertical slot cut in its upper end to receive the web 13. An attaching bar 14 is integrally formed with the web 13 and has bolt holes 15 adjacent its ends adapted to co-act with a pair of machine bolts for fastening the crown block in position. If a gin pole of the type employing but a single mast is used then a U-bolt extends around the mast and has its legs extended through the openings 15 and, of course, threaded to co-act with the nuts 16 which engage the attaching bar 14. An outwardly extending lug 16 is integrally formed with the bar 14 and is provided with openings 17 through which the rear guy wires are extended, the guy wires being fastened or suitably connected to the lug 16. Below the bar 14 and the lug 16 a hook 18 is provided and affords a means for fastening the dead line to the crown block.

Above the plate 11 an upwardly directing and forwardly curving arm 20 is provided, the arm being connected to the plate 11 by an enlarged web 21 which is integral with the arm and with the plate. The upper end of the arm 20 projects beyond or forwardly of the plate 11 and is substantially horizontal. On the upper side of the upper end of the arm 20 a notch or seat 22 is provided for the purpose of receiving the small rigging-up block used for stringing up the heavy main block. The portion of the arm 20 which underlies the seat or notch 22 is cut away or beveled inwardly, as shown to advantage in Fig. 6, so that the requisite clearance is provided to accommodate the hook of the rigging-up block so as to permit the block to hang vertically and swivel perfectly. Forwardly of the seat 22 and below the same an opening 23 is provided to receive the front guy wire. The opening 23 which is the point of attachment of the front guy wire to the crown block is located well above the block and forwardly thereof and is out of the way of the operating lines, the main block and the other elements of the

crown block. A main block supporting hook 25 is integrally formed with the web 21, plate 11 and front flange 12 and is designated to provide a support for the main or peg block. The hook 25 is located above the top of the mast and this effects the economy in the space between the hitch and the well and enables longer objects to be removed from the well than was possible with gin poles heretofore used. It is to be noted at this point that the hook 25 and the hook 18 are opposite each other and this feature causes the load to be applied squarely upon the top of the gin pole.

15 The crown block is especially designed to facilitate the stringing up for the purpose of pulling rods and tubing and otherwise caring for wells, especially oil wells. The advantages of the block may be appreciated when it is understood that the cost of the derrick ranges from five hundred to a thousand dollars. Most operators in small producing fields use derricks for drilling only. When a well has been finished a gin pole 20 is set up over the well for the purpose of operating the same. The cost of the gin pole and the crown block constituting this invention, with the crown block made of cast steel, is about fourteen dollars. The 25 guy wires and other auxiliary equipment, the cost of labor and materials, make the balance of the cost aggregating between sixty and seventy dollars.

I claim:

- 35 1. In combination with a gin pole, a crown block having a horizontal plate resting on the top of the gin pole and provided with depending flanges engageable with the gin pole to prevent backward or forward movement 40 of the crown block, the crown block also having a depending web engageable with the gin pole for the purpose of preventing lateral movement of the crown block, means for fastening the crown block to the gin pole, 45 an arm extending upwardly and forwardly from the plate and having a seat for a rigging-up block adjacent its upper end adapted to receive the front guy wire, a main block supporting hook integral with the plate and the arm and located above the plate, and a 50 guy line hook connected with the web and located on the opposite side of the crown block from the main block supporting hook.
- 55 2. In combination with a gin pole having a pair of standards, a crown block having a web fitted between the upper ends of the pair of standards to prevent lateral movement of the crown block, means co-operable with the standards for preventing backward and forward movement of the crown block, means for fastening the crown block to the standard, said crown block having an arm 60 extending upwardly and forwardly therefrom and provided with a guy line opening adjacent its upper end, a main block

supporting hook carried by the crown block above the gin pole and below the guy line opening, and a dead line attaching hook connected with the crown block on the opposite side thereof from the main block supporting hook.

3. In a device of the character described, a crown block comprising a horizontal plate having depending flanges at its front and back edges, a centrally disposed and downwardly extending web terminating in a dead line supporting hook, said web having an attaching bar provided with bolt holes, said bar having integral therewith a lug provided with guy line openings, an arm extending upwardly and forwardly from the plate and having its upper end provided with a seat to receive a rigging-up block, the arm being recessed below the seat to permit the rigging-up block to hang vertically and to swivel perfectly, said arm also having a front guy wire receiving opening adjacent its upper end, and a main block supporting hook integral with the plate, the front flange and the arm and rotated just above the plate.

4. In a device of the character described, a crown block adapted for use on the upper end of a gin pole and including a plate having depending flanges adapted to engage portions of the upper end of the gin pole to prevent fore and aft movement of the crown block, and a depending web also adapted to engage portions of the gin pole to prevent lateral movement of the crown block.

5. In a device of the character described, a crown block having a plate adapted to rest on the top of the gin pole, means for securing the plate in position, a main block supporting hook located just above the plate, an arm extending from the plate to a point above and forwardly of the main block supporting hook and having a guy wire receiving opening.

6. In a device of the character described, a crown block having a plate adapted to rest on the top of the gin pole, means for securing the plate in position, a main block supporting hook located just above the plate, and an arm connected with the plate and extending above the main block supporting hook and having a seat adapted to receive a rigging-up block.

7. In a device of the character described, a crown block having a plate adapted to rest on the top of the gin pole, means for securing the plate in position, a main supporting hook on said crown block and an arm connected with the plate and extending above the main block supporting hook and having a seat adapted to receive a rigging-up block, said arm being recessed below the seat to permit the rigging-up block to hang vertically and swivel perfectly.

ALEXANDER BOYNTON.
